WILHELM B. BRONANDER, OF MONTCLAIR, NEW JERSEY, ASSIGNOR TO AMERICAN MACHINE & FOUNDRY COMPANY, A CORPORATION OF NEW JERSEY.

MACHINE FOR LABELING CIRCULAR ARTICLES.

Application filed July 2, 1927. Serial No. 203,002.

This invention relates to an improvement in a machine for labeling circular articles, such, for example, as the so-called "Life-Saver" confection. Its main object is the production of a device to be used in connection with a wrapping machine, or independently, for applying a label to the circular article circumferentially, after the article has been wrapped. With this and other objects not specifically mentioned in view, the invention consists in certain constructions and combinations which will be hereinafter fully described and then specifically set forth in the claims hereunto appended.

In the accompanying drawings, in which like characters of reference indicate the same or like parts, Fig. 1 is a front elevation of a device constructed in accordance with the invention; Figs. 2 and 3 are respectively side elevation and plan view of the structure shown in Fig. 1; and Fig. 4 is a front elevation, on an enlarged scale, of the ejecting arm of the structure shown in Figs. 1, 2 and 3.

In carrying the invention into effect, there is provided a structure including two rollers or equivalent means supporting a label and a circular article to be labeled, a driving roller bearing down on and rotating the article to wind the label thereon, and means for raising said driving roller out of operative position to provide a fairway for incoming articles. In the best constructions contemplated, means is also provided for moving one of the supporting rollers out of operative position to provide a fairway for outgoing articles and further means is provided for ejecting the articles through the outgoing fairway; a conveyor is provided for receiving and transporting articles delivered to it by the ejecting means, and a coacting retainer is also provided for preventing displacement of the delivered articles on the conveyor. All of the above mentioned means and parts may be widely varied in construction within the scope of the claims, for the specific structure illustrating the invention is but one of many possible concrete embodiments of the same. The invention, therefore, is not to be restricted to the precise details of the structure shown and described.

Referring to the drawings: A cylindrical

article to be labeled, such, for example, as a wrapped package of "Life-Savers", together with a label therefor, is deposited on and is supported by two supporting rollers 5 and 6 between two positioning devices 7-7 actuated by moving parts of the wrapping machine in connection with which the labeling device is used. The label and article are emplaced while a driving roller 8 is in its raised position or out of its operative position wherein it bears down on and rotates the article to wind the label thereon. This raised position is shown by the dotted lines in Fig. 1, and the driving roller is moved into it intermittently, once for each cycle of operation of the device.

The rollers 5 and 6, supporting the label and article, are loosely mounted on shafts 9 and 10 respectively. The shaft 9 is supported by arms 11, and a spur 12 on the shaft 9 prevents said shaft from turning. The shaft 10 is supported in the side walls 13 of the frame of the device and has a spur 14 to prevent it from turning.

The driving roller, which is preferably provided with a rubber or other soft covering, is mounted on a shaft 15 supported in a bearing 17 extending from a swinging gear housing 16 in which the shaft 15 carries a spur gear 18 meshing with another spur gear 19 mounted on a shaft 20 and driven by a spur gear 21 loosely mounted on a shaft 22. The shaft 22 is carried by a bracket 23 and is clamped in the housing 16. A spur gear 24, mounted on a shaft 25, meshes with the gear 21. On the shaft 25, which is supported in a bracket 26 fastened to the table 27, is also mounted a gear 28 engaging a gear-segment 29 mounted on a shaft 30 supported in a bracket 31 attached to the table 27. The gear-segment 29 is rocked by a lever 32 also mounted on the shaft 30.

The lever 32 is actuated by a cam roller 33 which is adjustably mounted on an arm 34 attached to a sprocket 35 driven by a chain 36, the roller 33 engaging a cam track 37 in the lever 32. This cam track has two depressions 38 and 39 which, being concentric with the sprocket 35 when in their extreme positions corresponding to the ends of the stroke of the gear-segment 29, allow the cam roller 33 to pass along their entire

curved lengths without moving the lever 32. They thus cause the driving roller 8 to make a complete stop when on top of the package A, both before the actual rolling begins 5 and after the rolling is done.

While the positioning devices 7—7 are locating an article on the rollers 5 and 6, the driving roller 8 and the housing 16 supporting it are in their raised position or out of 10 operative position to provide a fairway for the incoming article. Before an article reaches the supporting rollers 5 and 6, a label is positioned thereon and held in place temporarily by means of a clamp 40.

15 The article, upon arrival on the rollers 5 and 6, presses the label B against them while at the same time the housing 16, actuated by a cam-operated rod 41, moves downward until the driving roller 8 presses down on 20 the article, and the paste roller 42 contacts with the label, depositing thereon a dab of paste. At this time, the driving roller begins to rotate and the label B which in the meantime has been released by the clamp 40, 25 is pulled between the rollers and wound around the article.

The paste roller 42 is carried between two pivot screws 43 placed in the arms of a lever 44 which swings on a shaft 45 supported by 30 a bracket 46 attached to the bearing extension 17 of the housing 16. The lever 47, mounted on a shaft 45, carries a post 48 which is connected with a post 49 on the lever 44 by a spring 50, thereby normally 35 keeping the latter lever pressed against a pin 51 in a lever 52 on the shaft 45, the pin 51 engaging a slot in one of the arms of the lever 44. In the raised position of the housing 16, the paste roller 42 contacts with a 40 paste drum 53 in the usual manner. A guard plate 55 is attached to the lever 44 and prevents the roller 8 from being splashed by paste.

An angle 56 is affixed to the extension 17 45 of the housing 16 and carries a hinge plate 57 having a pin 58 on which are mounted a lever 59 and a pair of fingers 60 having semi-circular shaped ends fitting the article A. The fingers 60 project into grooves provided in the driving roller 8 and in the supporting roller 6. A spring attached to the end of the lever 59 presses the fingers 60 50 against the article, serving as a guide for the label and pressing its overlapped ends together as the paste therebetween dries.

55 At the end of the label applying period, the ejecting arms 62, which are clamped on a shaft 63, are lifted up. The arms 62 have stationary fingers 63' and carry movable 60 fingers 64 pivoted on studs 65, the fingers 63' and 64 projecting into grooves provided for this purpose in the supporting rollers 5 and 6. In the uppermost position of the arms 62, the movable fingers 64 are pressed 65 against the bottoms of the grooves in the

70 roller 6, causing them to turn on the studs 65 and thus to close against the fingers 63' and thereby embrace the labeled article A. Springs 66, attached by screws 67 to the fingers 64 and held in V-shaped slots of 75 studs 68 on the arm 62, press the fingers tightly about the labeled article. This gripping process is performed while the roller 8 is at rest, hence no displacement can occur.

75 The lever 69, mounted on a shaft 70, lifts the arms 62 by means of a link 71 pivoted to a crank arm 72 on the hub of the arms 62. While the arms 62 are raised, the levers 80 11 with the roller 5 are moved outward, thereby lifting a lever 73 mounted on the hinge pin 58. By raising this lever, the fingers 60 are released from the article which then is held only by the fingers 63' and 64 85 on the arms 62 now having a clear path to the pockets 74 of the conveyor by which the labeled articles are discharged from the device.

90 The shaft 70 of the sprocket 75 driving the conveyor chain 76 has an intermittent motion imparted to it by a pawl arm 77 actuated by a rod 78. A guide lever 79 mounted loosely on the shaft 70 prevents the ejected article from falling back, this lever having an intermittent motion corresponding 95 to that of the conveyor and transmitted to it through a rod 80.

95 The fingers 63' and 64 are forced to spread apart again as soon as the labeled article has been deposited in the conveyor, 100 the arms 62 descending a short distance after the article has reached the pocket and thus causing the movable fingers 64 to press against the then stationary article, thereby turning the fingers.

105 Adjustable stop screws 81 carried by the bracket 31 constitute positive stops for the gear-segment 29 actuating the gear train of the driving roller 8, at both ends of its stroke, the carrying arm of said gear-segment having a stop-lug 82 engaging the screws 81. The stop screws 81 take up the clearance existing at the centre of the cam track 37 owing to the depressions 38 and 39, and prevent displacement of the label by 115 positively stopping the movement of the driving roller 8 before and after the labeling period.

110 In view of the foregoing, a detailed description of the operation of the device 120 is deemed unnecessary and is therefore omitted in the interest of brevity.

What is claimed is:

125 1. The combination with two rollers supporting a label and a circular article to be labeled, of a driving roller bearing down on and rotating the article to wind the label thereon, an arm in which said driving roller is mounted, gearing within said arm actuating said driving roller, and means for 130

raising said arm to move said driving roller out of operative position to provide a fairway for incoming articles.

2. The combination with two rollers supporting a label and a circular article to be labeled, of a driving roller bearing down on and rotating the article to wind the label thereon, an arm in which said driving roller is mounted, cam-actuated gearing within said arm actuating said driving roller, and means for raising said arm to move said driving roller out of operative position to provide a fairway for incoming articles.
3. The combination with two rollers supporting a label and a circular article to be labeled, of a driving roller bearing down on and rotating the article to wind the label thereon, means for intermittently actuating said driving roller, and means for intermittently raising said driving roller out of operative position to provide a fairway for incoming articles.
4. The combination with two rollers supporting a label and a circular article to be labeled, of a driving roller bearing down on and rotating the article to wind the label thereon, means for raising said driving roller out of operative position to provide a fairway for incoming articles, and means carried by said raising means for applying paste to a label for the article.
5. The combination with two rollers supporting a label and a circular article to be labeled, of a driving roller bearing down on and rotating the article to wind the label thereon, means for moving one of said supporting rollers out of operative position to provide a fairway for outgoing articles, and means for ejecting labeled articles through said fairway.
6. The combination with two rollers supporting a label and a circular article to be labeled, of a driving roller bearing down on and rotating the article to wind the label thereon, means for moving one of said supporting rollers out of operative position to provide a fairway for outgoing articles, and a swinging arm for ejecting articles through said fairway.
7. The combination with two rollers supporting a label and a circular article to be labeled, of a driving roller bearing down on and rotating the article to wind the label thereon, means for moving one of said supporting rollers out of operative position to
- provide a fairway for outgoing articles, a conveyor, and means receiving articles from said rollers and delivering them to said conveyor.
8. The combination with two rollers supporting a label and a circular article to be labeled, of a driving roller bearing down on and rotating the article to wind the label thereon, means for moving one of said supporting rollers out of operative position to provide a fairway for outgoing articles, a conveyor, and a swinging arm receiving articles from said rollers and delivering them to said conveyor.
9. The combination with two rollers supporting a label and a circular article to be labeled, of a driving roller bearing down on and rotating the article to wind the label thereon, means for moving one of said supporting rollers out of operative position to provide a fairway for outgoing articles, a conveyor, means receiving articles from said rollers and delivering them to said conveyor, and a retainer for preventing displacement of articles delivered to said conveyor.
10. The combination with two rollers supporting a label and a circular article to be labeled, of a driving roller bearing down on and rotating the article to wind the label thereon, means for moving one of said supporting rollers out of operative position to provide a fairway for outgoing articles, a conveyor, a swinging arm receiving articles from said rollers and delivering them to said conveyor, and a single rod and operative connections actuating said conveyor, said arm, and the moving roller.
11. The combination with two rollers supporting a label and a circular article to be labeled, of a driving roller bearing down on and rotating the article to wind the label thereon, means for moving one of said supporting rollers out of operative position to provide a fairway for outgoing articles, a conveyor, a swinging arm receiving articles from said rollers and delivering them to said conveyor, a retainer for preventing displacement of articles delivered to said conveyor, and a single rod and operative connections actuating the conveyor, the arm, the moving roller, and the retainer.

In testimony whereof, I have signed my name to this specification.

WILHELM B. BRONANDER.
